CLAIM

The ornamental design for a harness leash connector as shown and described.

DESCRIPTION

FIG. 1 is a perspective view of a harness leash connector showing our new design;

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof; and,

FIG. 8 is a perspective view of a harness leash connector showing our new design disposed on an animal harness.

The broken lines showing an animal harness in FIG. 8 depict environmental subject matter and form no part of the claimed design.

1 Claim, 8 Drawing Sheets(56)
